UNITED STATES PATENT OFFICE.

TOBIAS J. HOCK AND EMIL HAPPERSBERGER, OF SAN FRANCISCO,
CALIFORNIA.

COIN-CONTROLLED TELEPHONE-REGISTER.

SPECIFICATION forming part of Letters Patent No. 626,809, dated June 13, 1899.

Application filed July 20, 1898. Serial No. 686,400. (No model.)

To all whom it may concern:

Be it known that we, TOBIAS J. HOCK and EMIL HAPPERSBERGER, citizens of the United States, residing in the city and county of San Francisco, State of California, have invented an Improvement in Coin-Controller and Telephone-Registers; and we hereby declare the following to be a full, clear, and exact description of the same.

10 Our invention relates to an apparatus which is especially designed to register the number of coins which are placed in a telephone or other apparatus of this description and to at the same time indicate that a coin has been 15 placed in the slot and registered for purposes of communication.

It consists, essentially, in details of construction, which will be more fully explained by reference to the accompanying drawings, 20 in which—

Figure 1 is a view showing my invention applied to one form of registering mechanism. Fig. 2 is an end view of the hand-lever and its connections. Fig. 3 is a modification of 25 the actuating device.

The object of our invention is to construct a register which we have here shown as applicable for use in connection with coin-controlled telephones and by which the apparatus 30 remains disconnected and incapacitated for use until a coin has been placed in the proper chute and which will then release the instrument, so that it can be operated and will register the fact when the operation has been 35 completed. The construction is also such that the full stroke of the registering mechanism must be made before the parts can return to their normal position.

Various forms of registering devices may 40 be employed in conjunction with our apparatus, the essence of the register being the arrangement of a series of wheels or disks each carrying numbers from "1" to "10" and a means for intermittently advancing the first 45 until the ten figures have been successively exposed and then acting to move a figure upon the second and so on in the usual manner for registers.

In the present case we have shown a series 50 of superposed disks A, lugs B upon the disks, and a pawl C, which is turnable about the

common center of the disks, so as to engage with a lug corresponding with one of the numbers on the inner disk at each reciprocation of the lever which carries the pawl until the 55 disk has completed a revolution, when a slot in the periphery of the disk allows the pawl to drop and engage a lug upon the second disk, so as to advance it one figure and so on throughout all the disks to the periphery. The pawl 60 C is long enough to engage with all of the concentric - figured numbered disks and is fixed upon the lever-arm D, the fulcrum of which is here shown as being centrally of the disks. Around the fulcrum-point and, as here 65 shown, forming a part with the pawl-lever is a circular disk or head E. In the periphery of this disk is a notch F, and this notch is normally engaged by a hook-lever G, fulcrumed at H, so that one end of the lever will 70 engage with the notch in the periphery of the disk, while the other end is controlled by the action of a coin. This control by the coin may either be effected by the weight of the coin striking the end of the lever-arm, or, as 75 shown in Fig. 3, it may be effected by forcing the coin between a lever D' and a fixed point as it is inserted into the chute, through which it is guided to the receptacle and to which it eventually passes. In every case the movement of a lever acts to release the pawl-carrying lever D or D' and allow it to complete 80 its movement.

Fixed with suitable relation to the registering mechanism and also to the lever D is a 85 segmental rack I, the teeth of which are presented, so as to be engaged by a pawl J, which is carried by the lever-arm D. The lever-arm D projects through the side of the containing-case at any suitable or convenient 90 point, so that it may be grasped by the hand of the operator when he desires to complete a call, and whenever the coin has been dropped into the chute, as described, and the pawl-carrying lever D released the lever may then 95 be moved about in the arc of a circle sufficiently to advance the registering-disks and at the same time to indicate at the central office that the coin has been inserted. This indication is made by the completion of an electrical circuit and the usual light or other signal at the central office. It is effected by 100

means of a curved strip L, which is carried by the lever D, and the end of this strip forms a contact with the free end of a spring-plate 4, one end of which is fixed and connects with 5 a circuit-wire 2, while the other end is free and lies in the plane of a contact 5, to which the other circuit-wire 3 is connected. The curved strip L, being carried down by the lever D, engages the free end of the spring-plate 4 and presses it against the contact 5, which establishes a circuit and produces a light or other signal in the central office when the lever has fully completed its stroke. The strip L also acts as a guard and closure for 10 the slot in which the lever D moves, and thus prevents any tampering with the mechanism through this opening.

In order to prevent the lever D being drawn back without fully completing its stroke, the 20 pawl J, carried by the lever D, is arranged to engage with the curved rack I in such a manner as to allow the lever D to be moved forward after it has been released by the coin-controlled lever G, but which will prevent 25 the lever from being drawn back until it has completed its full stroke and has formed the contact by the arm L, as previously described. At this instant the pawl J is raised by an incline I' at the end of the curved rack I, and 30 when thus raised it is engaged by a holding-arm O, which retains it out of contact with the rack I, and thus allows the lever D to be drawn back. When the lever is thus drawn back so far that the pawl C will engage another of the lugs B, the pawl I is disengaged 35 from the device which holds it by the action of a presser-rod P, which is carried by the lever D and is slidable in a guide upon the lever. As the lever is drawn back the end of 40 this rod strikes a stop Q and is thus forced forward until it disengages the contacts with the holder O and disengages the pawl J, allowing it to again drop into contact with the rack I in readiness for another stroke of the 45 lever D. In this manner each time that a coin is introduced into the apparatus it acts either by gravitation or pressure upon the lever G and through this lever to disengage the lever D, by which the indicating-disks 50 are revolved, as previously described.

The pawl C, carried by the lever D, is pressed downwardly by a spring, as shown at R, so as to insure its engaging with the lugs upon the disks at each movement of the lever, and the disks are in turn prevented from 55 returning by springs S, which engage with notches a in the disks for that purpose.

Although we have described the invention as especially applicable to coin-controlled 60 telephones, it will be manifest that the device will be equally useful in conjunction with any

similar apparatus which is controlled by the introduction of a coin and in which it is desirable to register the operation.

Having thus described our invention, what 65 we claim as new, and desire to secure by Letters Patent, is—

1. In an apparatus of the character described, a series of registering-disks, a pawl-carrying lever fulcrumed so that by its forward and backward movement it advances the disks to register the movements, a pawl-and-ratchet mechanism by which the lever is prevented from returning until the forward motion is completed, a latching-lever by which 75 the lever is retained in its normal position when it has been returned thereto, said latching-lever being disengaged when a coin is introduced into the apparatus.

2. In an apparatus of the character described, a series of registering-disks, a pawl-carrying lever fulcrumed so that by its forward and backward movement it advances the disks to register the movements, a pawl-and-ratchet mechanism by which the lever is 85 prevented from returning until the forward movement is completed, a guard-plate carried by the lever and forming a closure for the slot through which the lever projects, electrical contacts, one of which is in the line of 90 travel of the guard-plate, and a switch actuated by said guard-plate at the end of its forward movement to close the circuit.

3. In an apparatus of the character described, a series of registering-disks, a pawl-carrying lever fulcrumed so that by its forward movement it advances the disks to register the movement, a stop mechanism carried by the lever, by which the latter is prevented from returning until the forward 100 movement is completed, contact-points with which wires from a central office connect, a spring switch-plate, one end of which is permanently connected with one of said contact-points, and the other end movable in line 105 with the other contact-point, a plate connected and reciprocable in unison with the movements of the register-actuating lever, said plate acting to force the free end of the spring-plate against said other contact-point where- 110 by a circuit is completed and the central office notified after the coin has been introduced and the forward movement of the lever completed.

In witness whereof we have hereunto set 115 our hands.
